UNITED STATES PATENT OFFICE.

PIERRE JACOMY, OF TOULOUSE, FRANCE, ASSIGNOR TO SOCIÉTÉ ANONYME LA CHEVRETTE, OF TOULOUSE, HAUTE-GARONNE, FRANCE.

LEVER JACK.

Application filed May 28, 1923. Serial No. 642,070.

To all whom it may concern:

Be it known that I, PIERRE JACOMY, a citizen of the French Republic, residing 40 Rue des Amidonniers, Toulouse, Haute Garonne, France, have invented new and useful Improvements in a Lever Jack, of which the following is the specification.

This invention relates to a system of lever jack, characterised by the use of a lever of the first order the point of application of the load of which is compelled to follow a rectilinear trajectory situated at an invariable distance from the fulcrum, owing to the use of a lever arm of determined profile, 15 sliding relatively to the fulcrum.

A lever jack thus characterised allows to instantaneously lift the load and, the distance from the fulcrum to the point of application being constant, the stress to be developed at the end of the large lever arm does not practically vary during the ascent of the load.

The accompanying drawing illustrates by way of example a form of construction of a 25 jack in accordance with the invention, more particularly devised for the lifting of motor vehicles.

Fig. 1 is a vertical section of the whole of the apparatus according to line A—A of 30 Fig. 3.

Fig. 2 is a side view with vertical section according to line B—B of Fig. 3.

Fig. 3 is a plan view with horizontal section according to line C—C of Fig. 1.

The apparatus comprises a frame 1, provided with a base 2 bearing on the ground, and having a vertical guide for slidably receiving a lifting rod 3 having on one side rack teeth 3' and jointed at its lower part 25 to the end 4 of a lever 5 the outer curved profile of which bears on a roller 6 mounted on an axis 7 secured in the side cheeks of the frame 1. The upper end or head of the lifting rod 3 is provided with a shoe 8 on which can be turned down a block or lift piece 9 permitting to use the apparatus under axles situated at different heights. This lift-piece 9 is pivoted at 10 on the shoe 8 and the bearing faces 11 and 12 under the load are, as usual, striated for ensuring 40 suitable adherence.

The curved lever 5 is brought back in the position which corresponds to the end of the lever stroke of the lifting rod 3, by a coil 55 spring 13 the ends of which are secured, on

the one hand, on the frame at 14 and, on the other hand, on the lever 5 at 15; the mechanical features of this spring are determined for holding the apparatus steady when the lever 5 is taken hold of. A tube 16 which constitutes the large branch of the lever fits, through its conical end 17, on the tail piece 18 of corresponding shape of the curved lever 5; the tube 16 is bent so as to be able, by variation of its angular position about 60 the axis of generation of its conical end, to set itself according to the required degree of inclination and to pass freely under the vehicle to be lifted.

A pawl 19 pivoted at 20 in a side housing of the frame 1 and subjected to the action of a counterweight 21, acts for releasing the lifting rod 3 at the time of its descent or for constantly holding it in all its positions of ascent. The counterweight 21 loose on the 65 axis 22 acts upon one or the other of the two radial abutments of this axis for angularly urging it in a direction or the other.

With its essential elements thus described the apparatus operates in the following manner:

The jack being placed under the vehicle with the lift-piece 9 or the shoe 8 arranged under one of the axles, the counterweight 21 is raised for causing the pawl 19 to come into 80 engagement with the rack 3'; it then suffices to exert a single pressure, at the end of the operating tube 16 for ensuring the ascent of the rod 3 and consequently the lifting of the vehicle and the pawl 19 held in 85 engagement with the rack 3 holds the said vehicle lifted at any desired height.

It is to be noted that, during the lifting operation, the curved lever 5 takes a bearing on the roller 6 and the axis 4 follows the 90 rectilinear movement of the rod 3, without the movement of the load relatively to the fulcrum of the lever materially varying; in practice, the useful stroke of the lifting rod 3 is equal to twice the small theoretical arm 95 of the system of lever.

For bringing back the load upon the ground, it suffices to send the counterweight 21 backward by using the tube 16, then to fit the said tube on the curved lever, to slightly lift the load for releasing the pawl 19 which automatically moves down outwardly 105 and to act upon the tube 16 for braking the descent of the vehicle.

As soon as the wheels touch the ground, 110

the apparatus is released and removed by holding it by the end of the lever, owing to the action of the spring.

What I claim as my invention and desire to secure by Letters Patent is:

A jack comprising a frame, a base at the lower end thereof, the frame and base being formed with a vertical guideway, a toothed lifting rod slidable in the guide, a housing formed on the side of the frame and communicating with the guideway, a shaft jour-

nalled through the housing, a pawl keyed to the shaft within the housing and engageable with the toothed lifting rod, a counterweight keyed to the shaft exteriorly of the housing, a curved lever pivoted to the lower end of the rod and extending through and above the base, and a roller journaled in the base for supporting the lever.

In testimony whereof I have signed my name to this specification.

PIERRE JACOMY.
